(No Model.)

C. GESCHWINDNER.
CAR COUPLING.

No. 472,992.

Patented Apr. 19, 1892.

UNITED STATES PATENT OFFICE.

CHARLES GESCHWINDNER, OF BROOKLYN, ASSIGNOR OF ONE-HALF TO
AUGUSTUS SINN, OF NEW YORK, N. Y.

CAR-COUPING.

SPECIFICATION forming part of Letters Patent No. 472,992, dated April 19, 1892.

Application filed January 8, 1892. Serial No. 417,409. (No model.)

To all whom it may concern:

Be it known that I, CHARLES GESCHWINDNER, of Brooklyn, New York, have invented an Improved Car-Coupler, of which the following is a specification.

This invention relates to a car-coupler in which the coupling-hooks are connected to and controlled by a weighted rock-shaft. By altering the position of such shaft the hooks 5 may be made to automatically couple or uncouple, and thus a coupler is produced which is of simple construction and positive in action.

The invention consists in the various features of improvement more fully pointed out in the claims.

In the accompanying drawings, Figure 1 is a vertical longitudinal section of the coupler, showing it closed; Fig. 2, a similar section showing it open. Fig. 3 is a top view thereof, and Fig. 4 a perspective of the sleeve.

The letters *a* represent two adjoining cars provided with bearings *b*, in which turn rock-shafts *c*. The ends *c'* of these shafts are bent at right angles and carry weights *c*². Each rock-shaft *c* is surrounded by a freely-turning sleeve *d*, which is slotted, as at *d'*, for the reception of a pin *c*³, secured to rock-shaft *c*. The sleeve *d* is provided with a slotted 30 link *d*², that engages a pin *e'* on the coupling-hook *e*. This hook turns upon a pin *f*, held by a forked bracket *f'*, bolted to the car *a*.

The rock-shafts *c* may be revolved backward or forward from the car-platforms by 35 means of a suitable chain *g* or similar attachment. When the shafts *c* are rocked backward, Fig. 1, the links *d*² will be raised and the hooks *e* swung down. When the shafts *c* are rocked forward, Fig. 2, the links *d*² will be 40 lowered and the hooks *e* swung up. The motion of the rock-shaft is in both cases imparted to the sleeve *d* by the pin *c*³ as soon as such pin engages either the front or rear edge of the slot *d'*. Until such engagement 45 takes place the shaft rocks without taking

the sleeve *d* with it, and the sleeve has to a like extent a limited independent motion on the shaft.

In use the shaft *c* is swung backward, Fig. 1, to bring the hooks down and then the cars 50 are pushed together, when the hooks will automatically engage the pins *f* and couple the cars. In this position the pins *c*³ bear upon the rear of the slots *d'*, and the rock-shafts thus tend to hold the hooks firmly 55 coupled. When the train has about completed its journey and nears the terminal depot, the shafts *c* are swung forward, so that pins *c*³ bear upon the front of the slots *d'* and the rock-shafts tend to open the hooks. In 60 this position of the shafts, however, the hooks will still maintain their engagement with the pins *f* as long as there is a pull on the train; but as soon as such pull ceases and the cars are slightly backed together, so that the hooks 65 release their hold on the pins, the weights *c*² will drop down, Fig. 2, thus swinging the hooks up and uncoupling the cars.

In case it is desired to uncouple the cars without first backing them together the hooks 70 may be readily raised off their pins by hand.

It will be seen that this coupling is of simple construction and can be readily opened and closed.

What I claim is—

1. The combination of rock-shafts *c* with sleeves *d*, mounted upon the same and having slotted arms *d*², and with hooks *e*, engaged by such arms, and pins *f*, engaged by the hooks, substantially as specified. 75

2. The combination of weighted rock-shaft *c*, having pin *c*³, with slotted sleeve *d*, engaged by said pin and having slotted arm *d*², and with hook *e* and pin *f*, substantially as specified. 80

CHARLES GESCHWINDNER.

Witnesses:

AUGUSTUS SINN,
F. V. BRIESEN.
